UNITED STATES PATENT OFFICE.

WILLIAM BROWN GIBSON, OF MORRILTON, ARKANSAS.

EARTH-AUGER.

SPECIFICATION forming part of Letters Patent No. 664,741, dated December 25, 1900.

Application filed March 6, 1900. Serial No. 7,504. (No model.)

To all whom it may concern:

Be it known that I, WILLIAM BROWN GIBSON, a citizen of the United States, and a resident of Morrilton, in the county of Conway and State of Arkansas, have invented a new and Improved Earth-Auger, of which the following is a full, clear, and exact description.

This invention relates to a class of augers employed for the formation of post-holes and for similar purposes, and has for its object to provide a novel simple earth-auger which is adapted for boring deeply into sand or clay for the production of oil or water wells and also for the formation of post-holes in the earth quickly and in a manner which enables the perfect removal of sand, clay, or earth by the auger as the work progresses.

The invention consists in the novel construction and combination of parts, as is hereinafter described, and defined in the claims.

Reference is to be had to the accompanying drawings, forming a part of this specification, in which similar characters of reference indicate corresponding parts in all the figures.

Figure 1 is a partly-sectional side view of the improved earth-auger with parts in operative adjustment and showing its operation when employed for boring a post-hole. Fig. 2 is a side view of the improvement, illustrating its application for boring a well-hole that is to be cased. Fig. 3 is a sectional side view of the earth-auger, showing operative details in closed adjustment. Fig. 4 is a bottom plan view of the device. Fig. 5 is a transverse sectional view showing operative details in opened adjustment and slightly changed in relative positions as compared with the same parts shown in Figs. 1, 2, and 3; and Fig. 6 is a transverse sectional view of the auger with parts arranged as shown in Fig. 5, but in closed adjustment.

The invention, briefly described, comprises a cylindrical hollow boring-head, a gate adapted to close an inlet-opening formed in the bottom wall of the head, a scoop-like excavator-blade extending down below the bottom of the head at one side of the opening therein, teeth projected from the bottom of the boring-head to loosen soil subsequently cut by the excavator-blade, a counterboring attachment for a diametrical enlargement of the hole bored by the excavator-blade, a handle

rod or bar for the boring-head and adapted by manipulation to rotate the latter and also to open and close the gate, and means to open and close the counterboring device manually operative from above the surface of the earth wherein a hole is being bored.

In the drawings, which represent the construction and operation of the invention, 10 indicates the cylindrical boring-head, which in size is proportioned to the diameter of the hole to be bored. In the bottom wall 10^a of the boring-head 10 a suitable opening *a* is formed, and along one radial edge of said opening a plate *b* is erected upon the bottom wall and inclined a suitable degree from the opening *a*, thus providing a stock-piece for supporting a cutter. Upon the plate *b* a cutter-blade 11 is secured by screws or other means, 70 so that a portion of the blade extends below the bottom wall 10^a, and a laterally-curved extension 12 of the blade 11 projects from the side edge thereof, the curvature of said extension adapting it to fit neatly in a shallow recess 75 formed to receive it in the inner side of the cylindrical wall of the boring-head 10, upon which it is secured.

A plurality of spaced teeth 13 project downwardly from the bottom wall 10^a, occupying 80 the imperforate portion of the same, as best shown in Fig. 4. A preferably tubular boring-bar 14 is provided, which extends at its lower end through a central perforation in the bottom wall 10^a of the boring-head 10, 85 and a nut *c* screws upon the threaded portion of said boring-bar that projects below the bottom wall. On the boring-bar 14 a short distance above the nut *c* a flat gate 15 in plate form is formed or secured, and said 90 gate, which is, in effect, a supplementary bottom, is cut away to form an opening therein which is of the same size as that of the opening in the fixed bottom wall 10^a, and, like said opening, has two radial edges.

The inner surface of the bottom wall 10^a is exactly level, and the lower surface of the segmental gate 15 is rendered level also to adapt it to closely engage with the top of the wall 10^a, upon which it seats. The boring-bar 14 is of a proper length to adapt it for effective service, and in case the auger is employed for boring post-holes the upper end of the bar is provided with a transverse handle-

piece 14^a. To loosely hold the boring-bar 14 centrally within the boring-head 10, said bar is inserted through a central orifice in a brace-piece 10^b, that is secured at its ends to opposite sides of the hollow head 10, as best shown in Fig. 3.

If the boring-bar is partially rotated when the segmental gate 15 is positioned above the opening *a* in the bottom wall 10^a, as shown in Fig. 6, the direction of rotatable movement being indicated in Fig. 5 by the curved arrow *x*, then the segmental gate will be turned on the bottom 10^a, so as to open the aperture *a*. The gate 15 will cease independently moving when the free edge of the notch therein, which approaches the stock-piece *b*, has contact therewith, as indicated in Fig. 5, and this contact of parts permits a further rotation of the boring-bar 14 in the direction mentioned to correspondingly move the boring-head 10, so that an engagement of the cutter-blade 11 with the surface of earth, sand, or clay will cause the cutter-blade to dig into the ground and plow as well as scoop and form a circular furrow therein.

Upon the boring-bar 14 a sleeve 16 is loosely mounted and normally is positioned with its lower end near the segmental gate 15. Upon the sleeve 16 a preferably slotted ear *d* is formed, whereon is pivoted one end of a link *e*, which at the opposite end is loosely connected to the lower end of a lifting-rod 17.

A rectangular opening *g* of proper area is formed in the side wall of the boring-head 10 a short distance above the bottom wall 10^a, and a plate-like cutter-blade 18 is hinged at one side edge upon a corresponding edge of this opening. The cutter-blade 18 is thus held to swing as a door in the opening *g*, and upon the top and bottom edges of said cutter-blade two similar guard-wings *i i* are formed or secured, which move freely in loose contact with corresponding edges of the opening *g*.

An arm *m* projects from the inner side of the cutter-blade 18 near the free cutting edge thereof, and upon the inner end of said arm a link *n* is pivoted by one end, its opposite end having pivotal connection with the lower end of the lifting-rod 17 adjacent to the end of the link *e*, that is pivoted thereto by a common pivot-bolt. It will be seen that by raising the lifting-rod 17 the cutter-blade 18 is drawn inwardly, so as to close it within the aperture *g*, and a depression of the rod will cause the cutter-blade 18 to swing outwardly.

The inner horizontal edges of the guard-wings *i i* are respectively bent at right angles, as shown in Figs. 1 and 3, which provides check-flanges *i* on the wings that fit against the concave inner surface of the hollow boring-head 10 when the cutter-blade 18 is swung outwardly, this contact of parts obviously limiting the outward movement of the cutter-blade to a suitable degree.

The lifting-rod 17 is preferably formed in two sections that have assured connection at

adjacent ends. As shown, a socket-nut *o* is formed on the lower end of the upper rod-section, and in said socket-nut is screwed the threaded upper end of the lower rod-section. An abutment-nut *p* is screwed upon the threaded upper end of the lower section of the lifting-rod 17, and in service this nut may have contact with the upper side of the brace-piece 10^b, through which the lifting-rod loosely passes, said lifting-rod when the nut is in such engagement coacting with the check-flanges *i* in defining the degree of outward swinging movement of the cutter-blade 18.

When the earth-auger is to be employed for boring post-holes and the like, such a proportionate length is given to the boring-bar 14 and the lifting-rod 17 as will adapt them for convenient manipulation by an operator. Assuming that the gate 15 is in opened adjustment, so as to provide a free passage at *a* for earth bored by the cutting-blade 11, as indicated in Figs. 1 and 5, to bore a hole a few feet deep in the ground the operator grasps the transverse handle-piece 14^a of the boring-bar 14 and places the boring-head 10 upright as well as the boring-bar at a point where a hole is to be made. The boring-head is now rotated by the operator in the direction of the arrow *x* in Fig. 5, and a circular furrow will be excavated by means of the cutter-blade 11, and the earth thus cut will be transferred upon the inclined surface of the cutter-blade 11 into the boring-head 10. After the boring-head has received a proper amount of earth the handle-piece 14^a is reversed in movement, which will correspondingly move the segmental gate 15 in the direction of the arrow *x'* in Fig. 6 until a radial edge of the opening in the gate contacts with the front side of the cutter-blade 11, thus completely closing the bottom of the boring-head.

In order to permit the free removal of the auger from the hole when this is desired, the cutter-blade 18 is swung outwardly before the boring operation is commenced, and said blade will as the work progresses cut a counterbore, thus enlarging the hole diametrically, the earth cut by the blade 18 passing into the hollow boring-head, being guided therein by the wings *i i*. The cutter-blade may be drawn inwardly by lifting the rod 17, as represented in Fig. 3, and this will enable the operator to freely raise the filled boring-head 10 from the post-hole for discharge of the earth with which it is loaded.

In boring a post-hole the hollow boring-head may not be of a capacity to hold sufficient dirt for completion of the boring by once filling the boring-head. Hence it will be necessary to return the auger to the partially-completed post-hole and repeat the boring operation (hereinbefore described) as often as is needed to give proper depth to the post-hole.

In Fig. 2 is shown the improved auger applied for the boring of a well in sand, earth, or clay, the only change needed in construc-

tion for such a use consisting in the lengthening of the boring-bar 14 and of the lifting-rod 17. It will be seen that after a certain depth has been reached by operating with 5 the auger as already described a casing-section 20 may be slid down into the counterbored hole and be supported by any suitable means, so that the lower end of the casing will be near to the cutter-blade 18. The 10 outer surface of the casing 20 should neatly fit against the interior of the auger-hole, and thus prevent any sand or earth from clogging the action of the boring-head.

The provision of the lifting-rod 17, which 15 is independent in its action from the boring-bar 14, permits the counterboring cutter-blade 13 to be operated while the boring-head is filled with earth, and the bottom thereof is closed, so that the cutter-blade may be re- 20 tracted readily to permit the free upward movement of the boring-head. This is a feature of manifest advantage and is claimed to be a novel one.

As the interior diameter of the casing 20 25 permits the free movement of the boring-head 10 in it, it will be evident that upon closure of the cutter-blade 18 and gate 15 after the boring-head is filled with borings the auger may be lifted from the well-hole, emptied, 30 and then be returned therein for a continuation of the boring operation. Obviously as the well-hole is deepened successive sections 35 of the casing 20 should be added, and thus complete the well-casing when the boring is finished.

Having thus described my invention, I claim as new and desire to secure by Letters Patent—

1. In an earth-auger, the combination with 40 a hollow boring-head, a boring-bar held to ro-

tate axially thereon, a segmental gate carried by the boring-bar, and adapted by a rotatable movement of said bar to open or close an opening in the bottom wall of the boring-head, and an excavator-blade in said opening, of a counterboring cutter-blade having one side edge hinged to a side edge of a lateral opening in the boring-head so as to swing therein, a guard-flange projecting laterally from a top edge and also from a bottom edge of the cutter-blade inwardly so as to direct earth cut by the blade into the boring-head, and means operating independently of the boring-bar to actuate the swinging cutter-blade. 45

2. In an earth-auger of the character described, the combination with a cylindrical boring-head partly open in its bottom, an axially-disposed boring-bar rotatable in and with the boring-head, working a gate to close 50 the opening in the bottom of the boring-head, and an excavator-blade in said opening, of a counterboring cutter-blade hinged by one side edge to a corresponding edge of a lateral opening in the boring-head, a vertically-reciprocating lifting-rod in the boring-head at one side of the boring-bar, a sleeve slidable on the lower portion of the boring-bar, an arm projected from the inner side of the cutter-blade, and links loosely connecting the 55 sleeve and arm with the lower end of the lifting-rod.

In testimony whereof I have signed my name to this specification in the presence of two subscribing witnesses.

WILLIAM BROWN GIBSON.
